UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY-CAR DRAFT-RIGGING.

1,178,095.

Specification of Letters Patent.

Patented Apr. 4, 1916.

Application filed February 6, 1915. Serial No. 6,411.

To all whom it may concern:

Be it known that I, JOHN F. O'CONNOR, a citizen of the United States, residing at Chicago, in the county of Cook and State of Illinois, have invented a certain new and useful Improvement in Railway-Car Draft-Rigging, of which the following is a full, clear, concise, and exact description, reference being had to the accompanying drawings, forming a part of this specification.

This invention relates to improvements in railway car draft riggings.

An object of the invention is to provide a draft rigging of simple construction and one wherein keys are employed as the stop members.

Another object of the invention is to provide a draft rigging having a yoke formed of commercial shape and particularly an H beam.

Other objects of the invention will more fully appear from the description herein-after.

In the drawing forming a part of this specification, Figure 1 is a vertical sectional view of a draft rigging embodying my improvements, the followers being shown in end elevation. Fig. 2 is a horizontal sectional view taken substantially on the line 2—2 of Fig. 3. Fig. 3 is an enlarged vertical transverse section taken substantially on the line 3—3 of Fig. 1 and Figs. 4 and 5 are detail perspectives of the follower and the yoke, respectively.

In said drawing, 10—10 denote wooden center sills of a car under-frame to the inner sides of which are secured longitudinally extending plates 11—11 having depending portions 12 to the outer sides of which are secured strengthening plates 13 having lower flanges 14 and upper flanges 15, the latter being bolted to said sills 10. On the inner sides of the plates 11 and above the lower faces of the sills 10, are secured longitudinally extending channels 16. The depending portions 12 and the plates 13 together form the draft sills or draft members and the same are provided with a front set of elongated upper and lower slots 17 and 18, an intermediate set of upper and lower slots 19 and 20 and a rear set of elongated upper and lower slots 21 and 22. Through the front slots 17 and 18 extend transverse keys 117 and 118 respectively; through the intermediate sets of slots 19 and 20 extend transverse keys 119 and 120, which keys are relatively fixed or stationary; through the rear set of slots 21 and 22 extend transverse keys 121 and 122 respectively. Mounted between the draft members is a yoke designated generally by the reference A, see Fig. 5, which yoke is in the form of an H beam having a central horizontal web 23, upper flanges 24—24 and lower flanges 25—25. The upper and lower flanges 24 and 25 are provided with a set of front slots 217 and 218 through which extend the keys 117 and 118, said slots being substantially of the same length as the width of said keys. A similar series of upper and lower rear slots 221 and 222 are provided in the yoke through which extend the keys 121 and 122. An intermediate series of upper and lower slots 219 and 220 are provided in the yoke A through which the keys 119 and 120 respectively pass, the slots 219 and 220, however, being longer than the keys to thereby permit the yoke to move forwardly over said keys which, as heretofore stated, are stationary. The horizontal web 23 of the yoke has a rear opening 26 therein and a central opening 27, the two openings being separated by an integral portion 28 of the web. The front portion of the web 23 is partly cut away as indicated at 30 and in which is received the rear end of the draw-bar 31 which, as shown, is provided with upper and lower shoulders 29—29 engaged by the rear edges of the keys 117 and 118. The openings 26 and 27 are provided for rear and front followers 32 and 33 respectively which followers, in normal position of the parts as shown in Fig. 1, occupy a substantially central position in said openings. Each of the followers is provided on its inner face with inwardly extending upper and lower bosses 34 on which are positioned the inner coils 35 of the twin arranged springs, the outer coils 36 of each spring being placed over the coils 35 as appears in Figs. 1 and 3, the upper outer coil resting upon the connecting portion 28 of the web of the yoke. Each of the followers 32 and 33 is furthermore provided with slots 37 on the outer edges thereof which engage and slide upon the edges of the web of the yoke forming the sides of the openings 26 and 27 so that the followers are supported by said yoke and yet are permitted to slide back and forth thereon, the position of the front

follower under full buff being shown in Fig. 2. Interposed between the front follower 32 and the rear end of the draw-bar 31 are upper and lower blocks 38—38 which are interposed horizontally between the keys 119 and 120 and the portion 39 of the web 23 which is left between the central opening 27 and the cut away portion 30. In normal position of the parts, the rear keys 121 and 122 form the rear shoulders or stops for the rear follower and the keys 119 and 120 form the front stops or shoulders for the front follower 32.

The operation of the device is as follows: 15 Under buff, the draw-bar moves inwardly thereby pushing the blocks 38 inwardly and the front follower. This compresses the springs against the rear follower 33 which is held stationary by the keys 121 and 122. 20 During this action, the yoke A does not move, inasmuch as it is held by the keys 119 and 120 which, in normal position of the parts, occupy the front ends of the slots 219 and 220. The inward or buffing movement of the draw-bar is limited by the engagement of the draw-bar with said keys 119 and 120 and also by the draw-bar engaging the web portion 39 and the front follower engaging the connecting web portion 30. 28. Under draft, the draw-bar shoulders engage the keys 117 and 118 thereby pulling the same forwardly, these keys in turn pulling the yoke A forwardly and thus the rear keys 121 and 122. The rear follower 33 is 35 thus moved forwardly and compresses the springs between it and the front follower 32 which is held from forward movement by the keys 119 and 120.

From the preceding description it will be 40 seen that my improved draft rigging avoids the use of side castings; it employs a cheap yet strong yoke which can easily be made from a commercially rolled shape by merely punching the proper slots and openings 45 therein; the draw-bar may be disconnected or removed by merely taking out the key 118; the entire device may be dropped down by removing all the keys; and the yoke A not only serves its normal function of a 50 yoke but in addition co-operates with the keys in supporting the parts of the draft gear.

Although I have herein shown and described what I now consider the preferred 55 embodiment of my improvements, yet it will be understood that changes and modifications may be made without departing from the spirit of the invention and all such changes and modifications are contemplated 60 as come within the scope of the claims appended hereto.

I claim:—

1. In a draft rigging for railway cars, the combination with draft members and draw-bar, of a yoke substantially H shape in cross-

section and having the central web thereof cut away to form follower pockets, followers in said pockets, and springs between said followers above and below said central web.

2. In a draft rigging for railway cars, the combination with draft members and a draw-bar, of a yoke formed from an H beam, followers, cushioning means between the followers, and removable stops for said followers.

3. In a draft rigging for railway cars, the combination with draft members and a draw-bar, of a yoke formed from an H beam, followers, cushioning means between the followers, and removable stops for said followers, said stops comprising transversely extending keys passing through slots in the flanges of said yoke.

4. A yoke for railway draft riggings comprising an H beam having the web thereof arranged horizontally, said web at the front end being cut away to receive the rear end of a draw-bar.

5. In a draft rigging for railway cars, the combination with draft members having a series of slots therein, of a yoke interposed between said draft members, said yoke comprising a single member having side flanges with slots therein, transversely extending keys passing through said slots in the yoke member and the draft members, followers interposed between said keys, and springs between said followers.

6. In a draft rigging for railway cars, the combination with draft members and a draw-bar, of a yoke, followers, springs, and means for supporting said draw-bar, yoke, followers and springs, said means comprising a plurality of pairs of keys, each pair comprising an upper and a lower key.

7. In a draft rigging for railway cars, the combination with draft members and a draw-bar having upper and lower shoulders, of a yoke member slidably mounted between said draft members, a pair of upper and lower, transversely extending, longitudinally movable keys extending through said yoke member and slots in said draft members, said keys being engaged by said shoulders of the draw-bar under draft to thereby pull the yoke member forwardly, shock absorbing means, and front and rear stops.

8. In a draft rigging for railway cars, the combination with slotted draft members and a draw-bar, of an H-shaped yoke, shock absorbing means, and transversely extending upper and lower sets of keys passing through slots of said yoke member and said draft members.

9. In a draft rigging for railway cars, the combination with draft members and a draw-bar, of a yoke formed from an H beam having the web thereof arranged horizontally, means for pulling said yoke forwardly

upon forward movement of the draw-bar, twin arranged springs, followers, and stops for said followers.

10. A yoke for railway draft riggings comprising an H beam having the web thereof arranged horizontally, said web being cut away to form two pockets near the center and rear thereof, each of which is adapted to receive a follower, said web being also cut away at the front end to receive the rear end of a draw-bar.

11. In a draft rigging for railway cars, the combination with draft members and a draw-bar, of shock absorbing means, a yoke of substantially H shape in cross section, and means for supporting said yoke, said means

comprising removable transversely extending keys.

12. In a draft rigging for railway cars, the combination with slotted draft members 20 and a draw-bar, of an H shaped yoke, springs, followers, means for connecting said yoke with the draw-bar under draft, means forming front stops for the front follower, and means forming rear stops for the 25 rear follower, each of said means comprising a pair of upper and lower transversely extending keys.

JOHN F. O'CONNOR.
